US00D511294S

(12) **United States Design Patent** (10) Patent No.: **US D511,294 S**
(45) Date of Patent: **** Nov. 8, 2005**

(54) **AIR HOSE REEL**

(75) Inventors: **James D. Kovacik**, Brecksville, OH (US); **Paul S. Blanch**, Broadview Heights, OH (US); **Joseph J. Smith**, Wooster, OH (US)

(73) Assignee: **Alert Stamping & Mfg. Co., Inc.**, Bedford Hts., OH (US)

(**) Term: **14 Years**

(21) Appl. No.: **29/212,258**

(22) Filed: **Aug. 30, 2004**

(51) LOC (8) Cl. **08-05**

(52) U.S. Cl. **D8/358**
